UNITED STATES PATENT OFFICE

AUSTIN EARLE CALKINS, OF WESTFIELD, AND LOUIS LASSEN, OF ELIZABETH, NEW JERSEY, ASSIGNORS TO STANDARD OIL DEVELOPMENT COMPANY, A CORPORATION OF DELAWARE

SAMPLING DEVICE

Application filed March 4, 1927. Serial No. 172,915.

This invention relates to improvements in fluid-sampling devices of the type in which a predetermined fraction of a stream of fluid is taken off and collected. The invention will 5 be fully understood from the following description, read in connection with the accompanying drawings, in which

Fig. 1 is a central vertical section through a preferred form of the improved device;

Fig. 2 is a side elevation, looking in the direction of the arrows and along line II—II, Fig. 1;

Fig. 3 is a transverse section on the line III—III, Fig. 2;

Fig. 4 is a transverse section on the line IV—IV, Fig. 2;

Fig. 5 is an enlarged transverse section on the line V—V, Fig. 4;

Fig. 6 is an enlarged side elevation of the 20 ratchet wheel;

Fig. 7 is a vertical section on line VII—VII, Fig. 6; and

Fig. 8 is a fragmentary view partly broken away showing the ratchet wheel and pin of 25 Fig. 1.

Referring to the drawings, reference numeral 1 denotes a housing having vertical perforations 2 and 3 the centers of which are respectively on the parallel lines A and B, shown in Fig. 4. A pair of perforations 4 and 5 (see Figs. 1 and 5) are formed in the central part of the housing. These are aligned 30 respectively with perforations 2 and 3 having their centers in lines A and B respectively.

Valve stems 2' and 3', carrying inlet valve 2^a and outlet valve 3^a, are slidably fitted in the perforations 2 and 3, and valve stems 4' and 5', carrying valves 4^a and 5^a, are slidably fitted in the perforations 4 and 5.

A bracket 6 is secured to the housing 1 by cap screws 7, or the like, which pass through the arms 8 and 9 of the bracket. As will be seen, especially from Figs. 2 and 4, the bracket embraces the housing and rests upon 45 it. The upper ends of the valve stems 2' and 3' are seated in recesses 10 and 11 in the body of the bracket. Springs 12 and 13, arranged respectively in these recesses, encircle the valve stems 2' and 3' and bear upon shoulders 50 14 and 15 formed thereon. The valve stems

4' and 5' have springs 12' and 13', respectively, for returning the valves 4^a and 5^a to seated position. Suitable packing is provided for the valve stems, as shown.

Rocker arms 16 and 17 are pivotally 55 mounted in slots 18 and 19 formed in lugs 20 and 21 extending upwardly from the housing 1. The outer ends of these arms lie within openings 22 and 23 in the valve stems 2' and 3'. The inner ends of the arms 16 and 17 rest respectively upon the heads of the valve stems 4' and 5'. A pair of slidable pins 24 and 25 are mounted in the bracket 6 and rest respectively upon the inner ends of the rocker arms 16 and 17.

A ratchet wheel 26 is rotatable on a shaft 27, which is journaled in bearings formed in standards 28 and 29 rising from the top of bracket 6. This wheel has cam surfaces 30, 30' on its two sides, see especially Figs. 1, 6 70 and 8. Between these surfaces are depressed areas 30^a and 30^b. The wheel 26 is rotated by a compound lever 31, 32 operating through a link 33 to move a pawl 34 which engages the teeth of the ratchet. The lever arm 31 is connected to the cross-head 35 of a pump, or to other suitable actuating means. A support 36 extends horizontally out from the bracket 6 to receive the end of the lever 31. A yoke 37 is mounted on the shaft 27 and pivotally 80 supports the link 33 which actuates the pawl 34.

The housing 1 has a lateral passageway 39 through which the fluid to be sampled is passed from a pipe 39^a. The passageway 39 85 intersects the perforation 2. Transverse passageway 40 affords communication between perforations 2 and 4 and passageway 41 between 3 and 5. A passageway 42 connects the perforations 4 and 5, and is closed at the outer end by a plug 42'. Passageways 40 and 41 are similarly closed by plugs 40', 41', respectively. A conduit 43, for withdrawing the sample, communicates with the perforation 3. The chambers 44, 45, beneath the valves 4^a and 5^a, are closed externally by plugs 44' and 45'.

The housing 1 is tapped to provide an opening 46, intersecting perforation 4, and adapted to allow flow of liquid through a 100

pipe 46^a back to the pump line, for a purpose to be described later. An air vent 47 communicates with the perforation 5.

The operation of the device is as follows, reference being made for example to its use in sampling a pumped stream of liquid:

Housing 1 is mounted in convenient relation to the pump and lever 31 is connected to cross-head 35. Passageway 39 receives liquid from the discharge line of the pump through pipe 39^a. Reciprocation of the cross-head forces pawl 34 forward, causing ratchet wheel 26 to turn in the direction of the arrow thereon (Fig. 1). In the position shown in that figure, pins 24 and 25 are forced upwardly against depressed surfaces 30^a and 30^b, on opposite sides of the ratchet wheel, by springs 12 and 13 operating through rocker arms 16 and 17. Valve stems 2' and 8' are pressed down on their seats by these springs. Accordingly, liquid can neither enter nor leave the housing.

As ratchet wheel 26 turns, pin 24 is depressed by engagement with cam surface 30'. This forces the inner end of rocker arm 16 downward, raising valve stem 2' and forcing valve stem 4' down so that valve 4^a is depressed slightly. This permits passage of liquid from the pump line through passageway 39, around the valve, and through opening 46 back to the pump line. At this time valves 3^a and 5^a are closed.

When cam surface 30' has passed beyond pin 24, this is lifted by spring 12' acting on rocker arm 16, until the pin rests against depressed surface 30^b. Consequently, valves 2^a and 4^a close. A sample of liquid is thus trapped in the passageways in housing 1. The volume of the sample may be accurately predetermined by the dimensions selected for these passageways, which in the aggregate may be referred to as the sample collecting chamber.

The cams 30 on the other side of the ratchet wheel are so arranged with respect to cams 30' that they operate to open the valves 3^a and 5^a a predetermined number of pump strokes after cams 30' have allowed the valves 2^a and 4^a to close. There is in all cases a positive segregation of inlet and discharge phases. The liquid trapped in the housing flows from the conduit 43 into a receptacle for the samples. The opening of valve 5^a serves to give access of air through opening 47 (Fig. 5) and permits ready flow of the sample. We prefer to use a separate valve for admitting air, but it is feasible to combine the functions of the air vent and liquid exhaust valves, as by allowing air to enter through the latter valve when opened.

It will be understood that the opening of valves 3^a and 5^a is effected by pin 25 forcing the rocker arm 17 downward, in the general manner above described for the actuation of arm 16.

The device described gives samples of constant volume at intervals which may be regulated by varying the number of teeth on the ratchet wheel 26, or the adjustment of the ratchet actuating levers, or both. In using the device to sample oil, we usually take a sample every fifty strokes of the pump. In this way a final composite sample which is truly representative of the oil is obtained. It will be noted that after the collection of each sample, there is a flow of liquid through the device before the next sample is taken. In this way all possibility of liquid remaining stagnant in the sampler is avoided.

Our invention is not limited to the ratchet and lever means of actuation. For example, pins 24 and 25 or rocker arms 16 and 17 may be operated by pressure-responsive diaphragms, clock-work, motors, or the like. The valve seats may be removable and valves of the ball type may be used if desired. By the provision of an adjustable plug or the like the volume of the sample chamber may be varied as desired.

Various changes and alternative arrangements may be made within the scope of the appended claims, in which it is our intention to claim all novelty inherent in the invention as broadly as the prior art permits.

We claim:

1. Sampling mechanism comprising a chamber adapted to contain a sample, a conduit connected to the chamber, means for normally passing liquid through said chamber and conduit, valve means operative at predetermined intervals to trap liquid in the chamber, and means for withdrawing the trapped liquid.

2. Sampling mechanism comprising a housing having a chamber therein adapted to contain a sample only in one operative position and to permit free flow of fluids in another operative position, a passageway for introducing fluid to be sampled from a source of supply into said chamber, said housing having a passageway for allowing flow from said chamber back to said source of supply, valve means operable to close said passageways, thereby trapping the portion of the fluid stream filling said chamber, and means for withdrawing the trapped fluid.

3. Sampling mechanism comprising a housing, a sample-collecting chamber therein, said housing having a passageway for introducing fluid to be sampled from a source of supply into said chamber, said housing having a passageway for allowing flow from said chamber back to said source of supply, valve means operable to close said passageways, thereby trapping the portion of the fluid stream filling said chamber, and means for withdrawing by gravity flow the trapped fluid, while the valve-controlled passage back to the source of supply is closed.

4. Sampling mechanism comprising a

housing, a sample collecting chamber therein and having a passageway for the introduction of fluid to be sampled from a source of supply, said housing having also a passageway for allowing liquid to flow normally through said chamber, valve means operable to close said passageways, thereby trapping the portion of the fluid stream filling said chamber, and means for withdrawing the 10 trapped fluid.

5. Sampling mechanism comprising a housing, a chamber therein, said housing having passageways through which a fluid stream to be sampled may enter and leave said chamber, 15 means for supplying a fluid stream for normal flow through said chamber, valves controlling said passageways, a conduit for withdrawing fluid from said chamber, an outlet valve controlling said conduit, means for 20 actuating the inlet valve to trap a sample of the fluid in said chamber while said outlet valve is closed, and means for actuating the outlet valve and opening communication with the air to permit the trapped sample to flow 25 from the chamber.

6. Mechanism according to claim 5 in which means for venting the chamber to the atmosphere are provided, and connections by which said means is simultaneously operated with 30 the outlet valve actuating means.

7. Sampling mechanism comprising a housing, a chamber therein, said housing having a passageway through which a liquid stream to be sampled may enter said chamber, a pair of inlet valves controlling said passageway, a conduit for withdrawing liquid from said chamber, a pair of outlet valves controlling said conduit, means for 35 opening the inlet valves and for closing the outlet valves to permit the filling of the chamber, means for closing the inlet valves to segregate the liquid in the chamber, and means operable subsequent to such closing for 40 opening the outlet valve to permit the liquid 45 to flow from the chamber.

8. Sampling mechanism comprising a housing, four valve stems in pairs therein, valves carried by said valve stems and serving respectively for controlling the inlet and 50 outlet of liquid, a support, rocker arms pivotally mounted thereon between the valve stems of each pair and engaging said stems for simultaneous actuation, said housing having an inlet passageway and an outlet passageway, a chamber within the housing and 55 with which these passageways communicate, and means for actuating the rocker arms in succession to open and close the inlet and outlet valves, whereby samples of liquid 60 are successively segregated in the chamber and discharged therefrom.

9. Mechanism according to claim 8, in which the means for actuating the rocker arms includes slidable pins for engaging the 65 rocker arms, and a rotary member having

cam surfaces arranged to operate the pins.

10. Mechanism according to claim 8, in which the means for actuating the rocker arms includes slidable pins for engaging the 70 rocker arms, a ratchet wheel having cam surfaces arranged to operate the pins, and a lever and pawl connection to operate the ratchet wheel.

11. In a sampling device comprising a housing having a chamber and a passageway connecting the chamber with a source of the liquid to be sampled, the improvement which comprises a pair of valves arranged to control the inlet and outlet of said passageway, 75 valve stems carrying said valves and slidably mounted in the housing, spring means normally holding one of said valves in closed position, means for simultaneously opening both valves, and means for releasing said first mentioned means, whereby the spring 80 controlled valve is permitted to return to closed position.
